UNITED STATES PATENT OFFICE.

CORNELIUS F. MADIGAN, OF BROOKLYN, NEW YORK.

CONTAINER.

1,222,226.

Specification of Letters Patent. Patented Apr. 10, 1917.

Application filed March 23, 1914. Serial No. 826,621.

To all whom it may concern:

Be it known that I, CORMELIUS F. MADIGAN, a citizen of the United States of America, and resident of the borough of Brooklyn, in the city of New York, county of Kings, and State of New York, have invented certain new and useful Improvements in Containers, of which the following is a specification.

This invention relates to containers and has for its object to provide an improved container for the purpose of safely conveying breakable articles, as bottles, eggs, and the like, and to provide at the same time very simple means which may be manufactured at a low cost and be readily shipped from place to place in collapsed condition and then be built up or assembled wherever desired to be used for the purpose of shipping such breakable articles from place to place.

For this purpose the invention is shown in the accompanying drawing and will be described more fully hereinafter and finally pointed out in the claims.

25 In the accompanying drawing,

Figure 1 is a perspective view of an embodiment of my invention specially adapted to the use of bottles,

30 Fig. 2 is a horizontal section taken on line 2—2 of Fig. 1,

Fig. 3 is a view of one of the web members adapted to receive a bottle,

35 Fig. 4 is a perspective view of interlocking web members specially adapted for conveying an egg,

Fig. 5 represents a front elevation of one of the web members shown in Fig. 4,

40 Fig. 6 represents an elevation of a fragment of the other web member of Fig. 4, showing one of its exterior locking notches, which exterior notches are adapted to engage interior notches of the web member of Fig. 5.

Similar reference characters indicate corresponding parts throughout the different 45 figures of the drawing.

In the illustrated embodiment of the invention shown in Figs. 1, 2 and 3 web members or webs 10 and 11 are interlocked at right angles to each other and inclosed in an outer 50 casing 41—42—43—44 in diagonal relation thereto. The web 10 is provided with a central cutout or opening 12 corresponding to the peripheral configuration of a bottle to be inclosed and the web 11 is also provided with 55 a central opening or cutout 20 also corre-

sponding to the shape of the bottle, and disposed on the axis of intersection of said webs. These openings register with each other and form a skeleton receptacle on said axis into which the bottle fits. The web 10 60 is provided at its upper end on its inner edge with a notch or slot 14 and at its lower end on its inner edge with a notch or slot 15. The web 11 is provided at its upper end at its outer edge with a notch or slot 18 and at 65 its lower end at its outer edge with a notch or slot 19. The webs 10 and 11 when assembled in operative position as shown in Figs. 1 and 2 are in angular relation to each other, preferably crossing at right angles. The upper outer edge of the web 10 passes through the slot 18 at the upper outer edge of the web 11 and the upper inner edge of the web 11 passes through the slot 14 at the upper 70 inner edge of the web 10. The lower outer edge of the web 10 passes through the slot 19 at the lower outer edge of the web 11 and the lower inner edge of the web 11 passes through the slot 15 at the upper inner edge of the web 10. 75

The webs are flexible, being constructed of pasteboard or other suitable material which permits the bending to facilitate assemblage thereof. The webs may be collapsed after the removal of the casing by swinging them 80 at their interlocking points or by disengaging said webs one from another after removal from the casing, and the casing may easily collapse after such removal.

85 Of course, instead of the shape shown in Figs. 1 and 3, other shapes may be shown; and instead of the shape of a bottle, the shape of an egg may also be shown. In Figs. 1 and 2 the bottle is shown in dotted lines, indicated by 40. The provision of 90 other shapes is clearly shown in Figs. 4, 5 and 6, in which the web 25 is provided with an opening 26 having extensions 27, and the web 28 is also provided with a similar opening 29 having extensions 30. The web 28 95 is provided at its upper end at its outer edge with a notch or slot 31 and at its lower end with a notch or slot 32, and the web 25 is provided at its upper end on its inner edge with a notch or slot 33 and at its lower end on its inner edge with a notch or slot 34, whereby the interlocking of the webs 28 and 25 may be conveniently carried out. The extensions 27 or 30 respectively serve to hold 100 the egg in suspended position so as to just 105 110

touch it with the tips of the fingers or extensions 27 and 30. This is clearly shown in Fig. 5, where an egg is shown in dotted lines, as indicated by 35, which is held by the tips 36 of the fingers 27. The slots 38 and 39 coöperate with the slots 31 and 32 of the web 28.

The webs or web members 25 and 28 when assembled in operative position are in angular relation preferably crossing each other at right angles, the upper outer edge of the web 25 passing through the slot 31 of the web 28 and the upper inner edge of the web 28 passing through the slot 38 at the upper inner edge of the web 25 and the lower edge of the web 25 passing through the slot 32 at the lower edge of the web 28 and the lower inner edge of the web 28 passing through the lower inner slot 39 of the web 25.

Both the interlocking webs 10 and 11 which have been shown to support a bottle or the like, and the interlocking webs 25 and 28 which have been shown to support an egg or the like, are intended to be placed into a box like that indicated in Fig. 1, but shown as broken away in that figure, the said box having a diameter equal to the length of each web, so that these webs form diametrical walls to the box, while the bottom of the box, as indicated by 41, contacts with the edges of the webs, and similarly the top, which, however, is not shown; whereas the side-walls of the box, indicated by 42, 43, 44 and 45, extend along the two side-edges of the webs 10 and 11, as clearly indicated in Fig. 1. This box and the walls thereof surround the interlocking webs, and also the supported article, as a bottle, egg, or the like. Similarly the webs 25 and 28 are also surrounded by a box like that shown in Fig. 1.

It will be noted that the webs shown in Figs. 4 to 6 are not provided with the cut 16. This is for the reason that these webs are of pliable paper and readily yield under pressure, whereby one web may be readily doubled up and inserted through the opening of the other and then permitted to expand, and thereby the interlocking brought about. This is possible up to a certain heaviness of material, but when the material becomes heavier, and especially the heavier cardboard, in that case the material would crack when it is bent, and in such case one of the side-portions of the webs is provided with a cut, as that shown by 16 in Fig. 1 and Fig. 3, and these two parts are then joined together either by metallic clasps 17, as shown, or by threads or the like. However, it is quite clear that the cut-out portions, and this part also, may be varied from the embodiments shown without departing from the invention.

It will also be noted particularly that by suspending the bottle or egg or other ar-

ticile in the webs as shown, and arranging these in an outside box, whenever the articles are conveyed from place to place they are suspended in position by these webs and by the box. Containers provided with my invention have been found especially advantageous in connection with the parcels post, whose operatives are not at all careful in the transportation of articles intrusted to them and who seem to find special and joyful recreation in the barbaric treatment of packages containing eggs. However, with my invention I have found that eggs and very delicate glass articles, as for instance, incandescent bulbs, may be conveyed and transported simply and safely, and that articles so packed can withstand a great deal of shock without the least injury.

Among the advantages of my invention are that the container may be manufactured in great quantities, may be shipped in collapsed form, and may be readily assembled wherever needed.

Of course it is very clear that besides bottles, eggs, incandescent bulbs, many other devices may be conveyed, as for instance, globes for arc-lamps, surgical appliances as test-tubes, thermometers, glass goods therefore, and the like, and many similar devices, all of which require at the present time very extensive and expensive packing.

I have shown several embodiments of my invention, but changes may be made therein without departing from the spirit of the invention as defined in the appended claims.

I claim:

1. A container comprising flexible webs interlocking in angular relation and provided respectively with cutouts disposed on the axis of intersection of said webs and jointly forming a skeleton receptacle corresponding to the peripheral contour of the article to be inclosed.

2. A container comprising flexible webs interlocking in angular relation and provided respectively with cutouts disposed on the axis of intersection of said webs and jointly forming a skeleton receptacle corresponding to the peripheral contour of the article to be inclosed, and a casing inclosing said interlocked webs.

3. A container comprising a rectangular casing, and separable flexible interlocking webs disposed at right angles to each other diagonally of said casing and provided with cutouts disposed on the axis of intersection of said webs and jointly forming a skeleton receptacle corresponding to the peripheral contour of the article to be inclosed.

4. A container comprising a rectangular casing, and separable flexible interlocking webs disposed at right angles to each other diagonally of said casing and provided with cutouts disposed on the axis of intersection of said webs and jointly forming a skeleton

receptacle corresponding with the shape of the article to be inclosed, the axis of the interlocking webs being substantially coincident with the axis of the article.

5 5. A container comprising webs, each having a cutout corresponding to the shape of the article to be inclosed, said webs being arranged angularly to each other with the axes of the two webs substantially coincident with the axes of the cutouts, and means holding said two webs in fixed angular position to each other.

10 6. A container comprising webs each having a cutout corresponding to the shape of the article to be inclosed and said webs being arranged angularly to each other in separable interlocking relationship, with the axes of the webs substantially coincident with the axes of the cutouts, and means hold-

ing said webs in fixed angular position to each other.

7. A container comprising webs each having a cutout corresponding to the entire outline shape of the article to be inclosed, said webs being arranged in angular relation, 25 the axes thereof being substantially coincident with the axes of the cutouts, said webs interengaging in angular relationship to each other when supporting an article and being collapsed flat upon each other when 30 not supporting an article.

In testimony, that I claim the foregoing as my invention, I have signed my name in presence of two subscribing witnesses.

CORNELIUS F. MADIGAN.
